ATTORNEY

UNITED STATES PATENT OFFICE

FRANK DENNIS VOIGT, OF SALEM, OREGON

DENTAL AMALGAM MIXER

Application filed August 27, 1928. Serial No. 302,207.

This invention relates to mixers and more particularly to devices of this character used by dentists in combining the ingredients used in making amalgam.

A primary object of the invention is to provide a simple and efficient mixing device for attachment to the arm of a dental engine which may be thrown into or out of operation at will and when in use has imparted thereto from the engine motor an oscillatory or swinging movement which thoroughly agitates and mixes the contents of the container carried by the attachment.

Another object is to provide a device of this character equipped with a capsule holder constructed to perform the double function of a holder and a rejector to facilitate the removal of the capsule when desired.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a side elevation of a dental engine arm with this improved attachment shown applied;

Fig. 2 is a similar view taken from the opposite side of the device;

Fig. 3 is an end elevation thereof;

Fig. 4 is a detail transverse section taken on the line 4—4 of Fig. 2;

Fig. 5 is a detail transverse section taken on the line 5—5 of Fig. 6; and

Fig. 6 is a horizontal section taken on the line 6—6 of Fig. 2.

In the embodiment illustrated a dental engine arm 1 is shown having the usual motor 2 connected therewith and provided with the regular pulley 3. Regular pulleys 4 (two in number) are arranged on the opposite end of arm 1 from the motor and a driving belt 5 which is always around these pulleys is trained around a cooperating pulley 11 carried by the attachment 10 constituting this invention.

The attachment 10 as here shown comprises an inverted U-shaped hanger 12 secured by a clamp 13 to the arm 1 at any desired location

thereon, it being readily removable when desired by simply unscrewing the clamping screw 14 which binds it on the arm. The hanger 12 has broad plate-like arms 16 and 17 in which is mounted the main driving shaft 15.

This main driving shaft 15 extends transversely through the arms 16 and 17 of the hanger and has an eccentric portion located between these arms and which is here numbered 19. The pulley 11 is fixed to one end of the shaft 15 and when it is desired to use the mixer the belt 5 is trained around this pulley as shown clearly in Figs. 1 and 2 so that motion may be imparted to the shaft 15 rotating it and causing the cam member 19 to oscillate or shake the mixer in a manner presently to be described.

Depending from the shaft 15 is a substantially L-shaped arm 20 having boxes 21 attached to one end thereof and which are located between the arms 16 and 17 of the hanger and encircle the portion 19 of the shaft 15. See Fig. 5.

The laterally extending lower arm 21^a of the mixer is made skeleton in form to form a cradle like support for a container 25 here shown in the form of a capsule.

This cradle like holder 21^a is equipped with a releasable latch member 22 which is pivotally connected at one end to one side of the holder and is adapted to swing over and span the capsule 25 and to have a releasable spring like engagement with the other side of the holder being equipped with a finger grip 23 to facilitate its operation. This fastening device 22 has a projecting portion or nose 24 located adjacent its pivoted end which when the latch is swung outwardly to its extreme position will engage the capsule 25 and lift it from its seat adapting it to be readily removed by the operator.

The free ends of the arms 16 and 17 of the hanger 12 are provided with registering apertures 26 and a head of the member 20 also has an aperture extending transversely therethrough which registers with these apertures 26 when the member 20 is in normal operative position, and these apertures are

designed to receive a headed pin or rod 27 forming the fulcrum which causes the member 20 to oscillate when in use. This pin 27 is preferably secured in position by a cotter pin 28 as shown in Fig. 6.

In the use of this attachment it having been clamped to the dental engine arm 1 as shown in Figs. 1 and 2 and the belt 5 trained around the pulley 11 motion is imparted to the shaft 15 through said belt and by the rotation of the shaft imparts an oscillatory or swinging movement to the member 20 whereby the container 25 is agitated and the contents thereof thoroughly commingled.

After the ingredients of the container 25 have been mixed to the desired point the device may be stopped in its movement by disconnecting the belt 5 from the pulley 11 and then by swinging the latch member 23 into open position the capsule will be raised and may be readily removed.

Without further description it is thought that the features and advantages of the invention will be readily apparent to those skilled in the art, and it will, of course, be understood that changes in the form, proportion and minor details of the construction may be resorted to, without departing from the spirit of the invention or its scope as claimed.

I claim:

1. An amalgam mixer including a depending supporting arm, a laterally extending cradle-like container holder projecting from said arm, means for detachably securing a container in said holder, said means having a container engaging element adapted to engage the container when the means is swung into open position to unseat the container.
2. An amalgam mixer including a depending supporting arm, a laterally extending cradle-like container holder carried by said arm, a releasable latch member pivotally connected at one end to one side of the holder and adapted to swing over and span the container to be held therein, means for releasably connecting the free end of said latch with said holder and a projecting nose located adjacent the pivoted end of said latch and adapted when the latch is swung outwardly to its extreme position to engage the container in the holder and lift it from its seat.

FRANK D. VOIGT.
